(57) **CLAIM**

The ornamental design for a projector equipment attached to vehicle, as shown and described.

DESCRIPTION

FIG. 1 is a front perspective view of the front, left, and top sides of a projector equipment attached to vehicle showing our new design;

FIG. 2 is a front view thereof;

FIG. 3 is a rear view thereof;

FIG. 4 is a right side view thereof, the left side view being a mirror image thereof;

FIG. 5 is a top plan view thereof, the bottom view being a mirror image thereof;

FIG. 6 is a cross-sectional front view taken along and in the direction of line 6-6 in FIG. 2;

FIG. 7 is a front perspective view thereof, but shown with different broken line subject matter in an exploded configuration of use; and,

FIG. 8 is another top plan view thereof, but shown in a usage state in an environmental view.

The broken lines shown in FIGS. 1 through 6 illustrate portions of the projector equipment attached to vehicle that form no part of the claimed design.

The broken lines shown in FIG. 7, showing a light source and a lens, an irradiated portion and a shadowed area, illustrate environmental structures and form no part of the claimed design. The broken lines shown in FIG. 8, showing a vehicle and an irradiated portion, illustrate environmental structures and form no part of the claimed design.

1 Claim, 8 Drawing Sheets
